[57] CLAIM

The ornamental design for a case for a video tape cassette, as shown and described.

DESCRIPTION

FIG. 1 is a front elevational view of a case for a video tape cassette showing my new design;

FIG. 2 is a rear elevational view thereof;

FIG. 3 is a left-side elevational view thereof;

FIG. 4 is a right-side elevational view thereof;

FIG. 5 is a top plan view thereof, the bottom plan view being a mirror image thereof; and

FIG. 6 is a cross-sectional plan view through section lines A—A of FIG. 1 showing internal features of the present design.

FIG. 4

FIG. 1

FIG. 6

FIG. 3

FIG. 2

FIG. 5
